HYDRAULICALLY OPERABLE SIDE-WALL
CORING TOOL

John H. Kirby, II, Houston, Tex.

Application December 5, 1946, Serial No. 714,324

5 Claims. (Cl. 255—1.4)

1

The invention relates to a sidewall coring or sampling tool which is self contained so as to be manipulated in a well bore and operated hydraulically to obtain sidewall samples. This application is a companion application to my co-pending applications Serial No. 630,199½, and Serial No. 667,798.

It is one of the objects of the invention to provide a sampling tool which may be quickly lowered into and removed from the well bore so as to obtain a sample.

Another object of the invention is to provide a sidewall sampling tool where the core member is extended laterally from the tool while the tool is urged toward the side of the bore to be sampled.

Another object of the invention is to provide a sidewall coring tool wherein a single motor effects rotation of the coring member and the simultaneous radial extension thereof.

Another object of the invention is to provide a sidewall sampling tool which is extended hydraulically while being rotated by the mechanical application of power.

A still further object of the invention is to provide a sidewall coring member extensible by a linkage mechanism which is in turn actuated by a hydraulic plunger.

Other and further objects of the invention will be readily apparent when the following description is considered in connection with the accompanying drawings, wherein:

Fig. 1 is a side elevation of the upper end of the coring tool illustrating the parts in section as the tool is lowered into the well bore.

Fig. 2 is a vertical sectional view of the lower portion of the tool and illustrating the coring tool as partly extended.

Fig. 3 is a section taken on the line 3—3 of Fig. 2 and illustrating a train of gears for effecting rotation of the coring member.

Fig. 4 is a section taken on the line 4—4 of Fig. 2 and illustrating the linkage connection for extending a coring member.

Fig. 5 is an illustrative view showing the tool in actual operation.

In Fig. 5 a well bore 2 has been drilled in the usual manner and it is now desired to sample a formation such as 3 so as to determine the contents thereof. With this in mind, the tool 4 is made up of the housing 1, the upper end of which is shown in Fig. 1. This housing is closed by an upper plug 8 threaded to a fishing nipple 9 which is in turn closed by a cap 10.

A removable nipple 11 has the cable 12 an-

2

chedored in the collar 13 therein. The pins 11 may be sheared upon sufficient pull on the cable in event the tool becomes lodged in the well so that the cable may be thus salvaged.

The conductor portion 14 of the cable is made up of a plurality of wires 15, three of which extend into the motor 16 while the fourth wire 17 serves as a signal wire as will be explained later. The motor 16 is a suitable type of reversible electric motor and is arranged to drive the shaft 20 and a reversible hydraulic pump 21. The pump may be utilized to pump oil or any other liquid and the lower portion 22 of the housing may be utilized as a reservoir for liquid to be drawn into and discharged from the pump. For purposes of simplicity the piping connections to and from the pump have been omitted.

The shaft 20 of the motor 16 extends downwardly therefrom as seen at 20 in the upper portion of Fig. 2. A pinion gear 25 thereon serves to drive a contacting pinion 26 which in turn drives a worm gear 27 which in turn meshes with a drive gear 28.

The drive gear 28 in turn engages an idler 29 which in turn drives an elongated pinion 30 which is best seen in Fig. 2.

The sampler member 33 is mounted in a carriage 34 which is laterally slidable upon the guide pins 35. In order to impart rotation to such coring tool 34, however, an idler 36 is shown as being driven by the pinion 30 but supported in the carriage 34 so as to turn the core tube drive gear 37. In this manner it seems obvious that the coring member 33 will be rotated while extended and retracted laterally of the housing.

The mechanism for extending and retracting the coring member 33 is shown in Fig. 2 as including a movable block 40 which slides in the interior liner 41 and is guided by the rollers 42. This block has an inclined slot 43 therein which receives a roller 44 mounted on the end of the link 45. This link is in turn pivoted on a pin 46 so that the slotted end 47 thereof engages the pin 48 on the side of the carriage 34.

The block 40 is connected to a plunger member 49 which is operable in a hydraulic cylinder 50 having a piping connection 51 to the pump 21. Thus when the liquid from the pump is directed into the connection 51, the plunger 49 will force the block 40 upwardly, causing the roller 44 to travel in the slot 43 and to rock the link 45 in a counter-clockwise direction as seen in Fig. 2. During this same manipulation, the operation of the motor turns the gear train so as to rotate the

drive gear 37 and cause the coring tool 33 to cut into the formation 3.

In order to determine when the coring member 33 has been extended the maximum amount, a tooth rack member 55 is shown as suspended from the block 40 and arranged to engage a pinion 56 which operates a rheostat 57. The wire 17 leads to this rheostat and thence to the surface where suitable switching mechanism will be operated when the rheostat shows the coring member to be fully extended. Such switch will reverse the motor 16 which in turn reverses the gearing mechanism and withdraws the liquid from the hydraulic cylinder 50 so as to retract the sampler member by returning the block 40 to its lowermost position.

In order to compensate for the volume of liquid utilized in the pumping operation, the closure cap 60 on the bottom of the tool is provided with a flexible diaphragm 61 exposed through the opening 62 to the well pressure. This diaphragm will breathe back and forth, depending upon the operation of the pump.

In order that the entire tool may be moved laterally of the well bore to the position shown in Fig. 5 so that the housing 7 of the tool will more closely approach the side of the well bore where the sample is to be taken, the tool has been equipped with upper and lower anchor members 70. Each of these anchor members embodies a hydraulic cylinder 71, a piston 72 therein and a plunger 73 which will be extended upon the application of hydraulic liquid to the back of the piston. This movement extends the pin 73 to engage the opposite side of the well bore of the sampler or coring member 33 and in this manner urges the entire tool laterally. A suitable choke may be provided in the hydraulic cylinder 50 so that the first application of hydraulic power may be applied to the upper and lower cylinder 71 so as to first extend the pin and move the housing over to sampling position and to thereafter extend the sampler 33.

Anchoring devices of a construction somewhat similar to those just described have been previously disclosed in my prior copending application, Serial Number 630,199 1/2, filed November 23, 1945 for a Sidewall Coring Device.

Any desired number of the tools may be coupled together and operated either independently or simultaneously as desired.

The casing 75 of Fig. 5 is usually positioned in a well and it is to be understood that the sample or core cutter 33 may be of a material which may cut through such casing and then on into the cement around the casing or into the formation as desired.

The operation of the device seems obvious in view of the foregoing description and broadly contemplates a hydraulic extensible sidewall coring member to which rotation is imparted in order to obtain a sample.

What is claimed is:

1. A sidewall coring tool for wells comprising a housing, a reversible motor therein, a reversible

5 pump operable thereby, a coring member, means operable from said motor including a carriage and a gearing to rotate said member, a linkage mechanism to move said carriage laterally of said housing, hydraulic means operable from said pump including a plunger to extend and retract said linkage.
